UNITED STATES PATENT OFFICE

118,221

DESIGN FOR AN AUTOMOBILE TRUCK

Clifford Brooks Stevens, Milwaukee, Wis.

Application July 14, 1938, Serial No. 78,489

Term of patent 3½ years

To all whom it may concern:

Be it known, that I, Clifford Brooks Stevens, a citizen of the United States, residing at Milwaukee, in the county of Milwaukee and State of Wisconsin, have invented a new, original, and ornamental Design for an Automobile Truck, of which the following is a specification, reference being had to the accompanying drawings, forming part thereof.

Both sides of the vehicle have the same appearance as shown in Figure 1.

I claim:

The ornamental design for an automobile truck, as shown and described.

CLIFFORD BROOKS STEVENS.
